US00D729552S

(12) **United States Design Patent**
Morales et al.

(10) **Patent No.:** US D729,552 S
(45) **Date of Patent:** ** May 19, 2015

(54) **BAIT RACK**

(71) Applicant: **LiphaTech, Inc.**, Milwaukee, WI (US)

(72) Inventors: **Christopher H. Morales**, Milwaukee, WI (US); **Sandy Morales**, Milwaukee, WI (US); **Daniel M. Machak**, Racine, WI (US); **Raymond W. Finke**, Memphis, TN (US); **James J. Doll**, Bayside, WI (US)

(73) Assignee: **LiphaTech, Inc.**, Milwaukee, WI (US)

(**) Term: **14 Years**

(21) Appl. No.: **29/501,511**

(22) Filed: **Sep. 4, 2014**

(51) LOC (10) Cl. **06-06**

(52) U.S. Cl.

USPC **D6/678.4**

(58) **Field of Classification Search**

USPC D6/396, 449, 462, 491–492, 509–511, D6/524–525, 546, 672, 675, 675.4, 675.5, D6/678.4, 678.5; 248/176.12, 175, 176.1; 211/16, 71.01, 85.24, 88.04, 90.03; D7/601–602; D3/304, 306

(57) **CLAIM**

The ornamental design for a bait rack, as shown and described.

DESCRIPTION

FIG. 1 is a perspective view of an embodiment of the claimed design;

FIG. 2 is a perspective view of the claimed design of FIG. 1;

FIG. 3 rear view of the claimed design of FIG. 1;

FIG. 4 is a front view of the claimed design of FIG. 1;

FIG. 5 is a left side view of the claimed design of FIG. 1;

FIG. 6 is a right side view of the claimed design of FIG. 1;

FIG. 7 is a top view of the claimed design of FIG. 1; and,

FIG. 8 is a bottom view of the claimed design of FIG. 1.

The ornamental design which is claimed is shown in solid lines in the drawings.

1 Claim, 7 Drawing Sheets
